UNITED STATES PATENT OFFICE

1,933,746

TOILET SEAT

Archibald I. McColl, Kalamazoo, Mich.

Application September 8, 1931. Serial No. 561,533

12 Claims. (Cl. 4—247)

The main objects of this invention are:

First, to provide a toilet seat in which portions thereof are covered with paper, the paper being automatically shifted by the raising of the seat.

Second, to provide a toilet seat with a sanitary cover for the supporting portions thereof, which may be easily manipulated for the placing of fresh rolls of paper and the removal of used rolls.

Third, to provide a structure having these advantages, which is very positive in operation, the seat covering paper being automatically fed without likelihood of its being fractured or broken.

Fourth, to provide improved automatic lifting means for the seat.

Fifth, to provide improved driving means, whereby the paper seat covering is renewed only during the lifting of the seat.

Sixth, to provide means whereby the take-up or winding rolls are locked against reverse rotation at all times.

Seventh, to provide readily accessible and interchangeable supply and winding spools.

Eighth, to simplify and improve toilet seats of the type particularly set forth and claimed in my Patent No. 1,843,778, issued February 2, 1932.

Ninth, to divide the hollow side members into separate supply and winding roll compartments whereby to keep the supply rolls sanitary.

Tenth, to provide improved clutching means whereby the rolls are actuated upon the lifting of the seat but are disconnected upon the lowering of the seat.

Eleventh, to provide the side members with detachable sections whereby the supply and take-up roll compartments are readily accessible.

Objects relating to details and economies of my invention will appear from the description to follow. The invention is defined and pointed out in the claims.

A structure which is a preferred embodiment of my invention is illustrated in the accompanying drawings, in which:

Fig. 1 is a plan view of my improved toilet seat.

Fig. 2 is a fragmentary side elevation of the toilet seat in raised or normal position.

Fig. 3 is an enlarged fragmentary view partially in plan and partially in section.

Fig. 4 is an enlarged fragmentary vertical section taken on a line 4—4 of Figs. 1 and 3.

Fig. 5 is an enlarged transverse section taken on a line corresponding to 5—5 of Figs. 1 and 3.

Fig. 6 is an enlarged fragmentary vertical section taken on a line corresponding to line 6—6 of Figs. 1 and 3.

Fig. 7 is a fragmentary transverse section taken on line 7—7 of Fig. 4, and

Fig. 8 is a transverse section taken on line 8—8 of Fig. 4.

Fig. 9 is a perspective view of a connection member.

Referring to the drawings, No. 1 represents the bowl of a water-closet or the like, with which the seat 2 is associated. The seat 2 is of general U-shape facing forwardly, the side members 3 converging inwardly as illustrated. The rear or cross member 4 and the side members 3 are chambered or hollow, being preferably formed of aluminum castings or of sheet metal which may be enameled or finished as desired.

The side members 3 are divided into separate supply roll and take-up or winding roll compartments 5 and 6 by vertical walls 7 of substantially inverted L-shape, which are disposed longitudinally of the side members and are secured to the tops thereof by a welding at 8. The lower ends of the walls 7 are provided with offset portions 9 which are adapted to coact with similar offset portions provided on the spaced retaining members 10 of the detachable bottom sections 11. Take-up and supply spools 12 and 13 are rotatably disposed in the compartments 6 and 5 respectively. The side members are provided with opposed longitudinal slots 14 and 15 through which the webs or sheets extend from the supply and take-up rolls over the tops of the side members.

The bowl 1 is provided with spaced supporting posts 16 which carry a forwardly facing supporting yoke or member 17 of substantially U-shape, having alined inwardly extending journals 18 which coact with bearing 19 provided therefor in the sides of the rear or cross member 4.

Segmental gears or racks 20 are fixed to the inner ends of the journals 18 and mesh with beveled gears 21 provided on the gear wheel 22 which is rotatably carried by the vertical spindle 23. The spindles 23 are tubular and are secured in place by means of screws 24 which extend through the top and bottom walls of the rear seat member 4. The gear wheels 22 mesh with beveled pinions 26 carried by the shafts 27. The arrangement of the gear wheels 22 and their meshing gears is such that when the gear wheels are rotated, the seat is swung about the journals 18 and also the pinions 26 are rotated so as to actuate the take-up rolls.

The gear wheels 22 are automatically rotated by means of a tension spring 28 which connects them and is disposed within the hollow rear member 4, as illustrated. The gear wheels 22 are pro-

vided with upwardly extending studs 29 which rotatably carries sleeves 30, having annular peripheral grooves 31 constituting seats for the ends of the tension spring 28. The tension spring 28 is adapted to rotate the gear wheels toward each other at all times so that when the seat is released the spring causes the gear wheels 22 to rotate and drive the racks 20 so as to swing the seat upwardly about the journals 18. The arrangement is such that the spring 28 exerts a greater force when the seat is in a horizontal position than when it is in its raised or vertical position. This is due to the fact that as the spring 28 moves the studs 29 together in raising the seat, it weakens itself in the manner of tension springs.

The beveled gears 26 drive the take-up rolls through a driving clutch 32 and a ratchet device 33. The driving clutch is adapted to provide a driving connection between the pinions 27 and the take-up spools 12 when the seat is raised by the spring 28 whereby the paper covering is fed or renewed on the side members and to permit the seat to be lowered without connection between the spindles 27 and the take-up spools 12. The driving clutches 32 preferably consist of substantially rectangular driving clutch members 34 which are provided with spring seats or recesses 35 and opposed grooves 36. The driving clutch member 34 is surrounded by a drum-like driving clutch member 37. Pawls 38 are disposed between the clutch member 34 and the drum 37. The pawls 38 are provided with knuckles 39 which are disposed in the grooves 36 and spring recesses 40 alined with the spring recesses 35. Compression springs 41 are carried by the recesses 35 and 40 for forcing the pawls into engagement with the inner periphery of the drum 37. The faces of the pawls which contact with the drum are serrated or toothed for facilitating their engagement with the drum. When the clutch member 34 is turned in a clock-wise direction, as illustrated by Fig. 7, the pawls pivot in the grooves 36 against the force of the springs 41 which permits the clutch member 41 to rotate free of the drum 37. However, when the clutch member 34 is rotated in a counter clockwise direction, as indicated by Fig. 7, the pawls engage the drum 37 and cause it to rotate with the driving member.

The drum 36 is supportingly embraced by a sleeve 42 which is fixed relative to the seat and extends forwardly beyond the drum 37. This sleeve 42 constitutes a stationary supporting element which is associated with the holding ratchet 33. The holding ratchet consists of the member 43 which is integrally connected to the driven member 37 of the clutch and which is provided with detents 44 and springs 45 which are similar in construction and operation to those described above in connection with the driving clutch. Their operation is such that when the drum 37 is positively driven, the detents 44 slip freely within the sleeve 42. When, however, it is adapted to rotate the clutch member 43 in a reverse direction, then the detents 44 lock in engagement with the sleeve 42. This arrangement positively obviates the possibility of the reverse rotation of the take-up spools 12 and prevents the device from operating in a reverse direction.

The sleeve 42 is provided with rearwardly extending upper and lower portions 46 and 47 which are disposed between the upper and lower walls of the rear member 4 and the ends of the spindle 23. In this manner the sleeve 42 is held stationary with respect to the seat at all times.

75 A journal 48 is connected to the ratchet mem-

ber 43 and extends forwardly into the take-up roll compartment 6 for engagement with the take-up spool 12. The latter is provided with a cup-shaped connecting member 49 of fiber or the like, having a non-circular hole 50 which registers with a non-circular part on the journal 48, as clearly illustrated by Fig. 4. While I prefer to use a hexagonal journal and hole for the cups 49, it will be appreciated that any non-circular or polygonal connection may be made.

The pinions 27 and the journals 48 are rotatably supported by spaced vertical members 51 and 52 which are in turn carried by the fixed sleeve 42.

The spools are rotatably carried between supporting discs 53 and 54. The inner supporting discs 53 of the take-up spools 12 are urged outwardly into engagement therewith by means of compression springs 55 disposed between the walls 56 and said discs. The supply spools 13 are held in position between the supporting discs 53 and 54 by means of inner journals 57 carried by the discs 53 which are disposed in cup-shaped bearing members 58 in which are housed compression springs 59 for urging the supporting discs 53 outwardly into engagement with the supply spools 13. The cup-like bearings 58 are integral with the walls 56 which are welded to the interior of the side members at 60 and 61.

The supply spool 13 is, of course, wound with a sheet or web 62 of suitable material such as paper to form the supply roll 63. As pointed out above, the sheet 62 passes from the supply roll 63 through the opening 14 over the top of the side member 3, thence downwardly through the opening 15 and on to the take-up spool 12 to constitute a take-up roll 64. The take-up and supply rolls are readily renewable by merely removing the bottom section 11 which is detachably secured to the wall 7 as described above.

In operation, when the seat is released from a horizontal position, it is raised by the force of the tension spring 28, as described above, which at the same time actuates the take-up spool 12 through the driving clutch 32 to renew the paper covering on the top of the side members 3. When the seat is again lowered, the clutch 32 disconnects the take-up rolls from the pinions 27 in the manner described above.

From the above description, it will be apparent to those skilled in the art that the device is relatively simple in construction and highly efficient in operation. Very few working parts are required, yet the device works positively and accurately to accomplish the desired purpose.

I have not attempted to illustrate or describe various modifications and adaptations which I contemplate, as it is believed that this disclosure will enable those skilled in the art to make such modifications and adaptations as may be desired.

Having thus described my invention what I claim as new and desire to secure by Letters Patent is:

1. A toilet seat of the class described comprising a forwardly facing U-shaped seat having 140 chambered rear and side members, the side members having top sections provided with roll holders, vertical longitudinal walls depending from the tops thereof and constituting partitions separating the supply and winding rolls and bottom 145 section supporting means, and bottom sections detachably carried by said walls, supply and winding rolls mounted in parallel relation in said holders, the winding rolls being provided with journal engaging members at their rear ends, the 150

- seat side members having slots in the sides thereof through which a web of paper may be passed from the supply rolls around the tops of the side members to the winding rolls, and the side walls of the rear seat member having axle receiving openings, spaced alined seat supporting journals arranged in said openings, gear racks secured to the inner ends of said journals, bevel gears pivoted within said rear member and meshing with said gear racks, a tension spring disposed longitudinally within said rear member and connecting said gears, whereby to rotate them together to lift said seat about said journals, the force of said spring being greatest when said seat is in a horizontal position and weakest when said seat is in a raised or vertical position, pinion gears meshing with said bevel gears for turning said supply rolls, journals connected to said pinion gears, driving clutches disposed in the connection between said bevel gears and said journals for causing said pinion gears to rotate said journals only in one direction, and holding ratchets disposed in the connection between said driving clutches and said journals for preventing the reverse rotation of said winding rolls.

2. A toilet seat of the class described comprising a forwardly facing U-shaped seat having chambered rear and side members, the side members having top sections provided with roll holders, vertical longitudinal walls depending from the tops thereof and constituting partitions separating the supply and winding rolls and bottom section supporting means, and bottom sections detachably carried by said walls, supply and winding rolls mounted in said holders, the winding rolls being provided with journal engaging members at their rear ends, the seat side members having slots in the sides thereof through which a web of paper may be passed from the supply rolls around the tops of the side members to the winding rolls, and the side walls of the rear seat member having axle receiving openings, spaced alined seat supporting journals arranged in said openings, racks secured to said journals, gears pivoted within said rear member and meshing with said racks, a tension spring disposed longitudinally within said rear member and connecting said gears, whereby to rotate them together to lift said seat about said journals, the force of said spring being greatest when said seat is in a horizontal position and weakest when said seat is in a raised or vertical position, pinion gears meshing with said gears for turning said supply rolls, journals connected to said pinion gears, driving clutches disposed in the connection between said gears and said journals for causing said pinion gears to rotate said journals only in one direction.

3. A toilet seat of the class described comprising a forwardly facing U-shaped seat having chambered rear and side members, the side members having top sections provided with roll holders, supply and winding rolls mounted in said holders, the winding rolls being provided with journal engaging members at their rear ends, the seat side members having slots in the sides thereof through which a web of paper may be passed from the supply rolls around the tops of the side members to the winding rolls, and the side walls of the rear seat member having axle receiving openings, spaced alined seat supporting journals arranged in said openings, racks secured to said journals, gears pivoted within said rear member and meshing with said racks, a tension spring disposed longitudinally within said rear member and connecting said gears, whereby to rotate them together to lift said seat about said journals, the force of said spring being greatest when said seat is in a horizontal position and weakest when said seat is in a raised or vertical position, pinion gears meshing with said gears for turning said supply rolls, journals connected to said pinion gears.

4. A toilet seat of the class described comprising a forwardly facing U-shaped seat having chambered rear and side members, the side members having top sections provided with roll holders, supply and winding rolls mounted in said holders, the winding rolls being provided with journal engaging members at their rear ends, the seat side members having slots in the sides thereof through which a web of paper may be passed from the supply rolls around the tops of the side members to the winding rolls, and the side walls of the rear seat member having axle receiving openings, spaced alined seat supporting journals arranged in said openings, racks secured to said journals, gears pivoted within said rear member and meshing with said racks, a tension spring disposed longitudinally within said rear member and connecting said gears, whereby to rotate them together to lift said seat about said journals, the force of said spring being greatest when said seat is in a horizontal position and weakest when said seat is in a raised or vertical position, pinion gears meshing with said gears for turning said supply rolls, journals connected to said pinion gears, driving clutches disposed in the connection between said gears and said journals for causing said pinion gears to rotate said journals only in one direction, and holding ratchets disposed in the connection between said driving clutches and said journals for preventing the reverse rotation of said winding rolls.

5. A toilet seat of the class described comprising a forwardly facing U-shaped seat having chambered rear and side members, the side members having top sections provided with roll holders, supply and winding rolls mounted in said holders, the winding rolls being provided with journal engaging members at their rear ends, the seat side members having slots in the sides thereof through which a web of paper may be passed from the supply rolls around the tops of the side members to the winding rolls, and the side walls of the rear seat member having axle receiving openings, spaced alined seat supporting journals arranged in said openings, racks secured to said journals, gears pivoted within said rear member and meshing with said racks, a tension spring disposed longitudinally within said rear member and connecting said gears, whereby to rotate them together to lift said seat about said journals, the force of said spring being greatest when said seat is in a horizontal position and weakest when said seat is in a raised or vertical position, pinion gears meshing with said gears for turning said supply rolls, journals connected to said pinion gears.

6. A toilet seat comprising a hinged chambered seat of U-shape having side members divided by internal vertical longitudinal partitions into separate supply and winding roll compartments.

- bottom sections detachably carried by said partitions, supply and winding rolls disposed in said compartments having sanitary connecting webs extending over the tops of said side members, means for lifting said seat about its hinge, and means driven thereby for actuating said rollers to renew the webs on the tops of said side members. 80
7. A toilet seat comprising a hinged chambered seat of U-shape having side members divided by internal vertical longitudinal partitions into separate supply and winding roll compartments, bottom sections detachably carried by said partitions, supply and winding rolls disposed in said compartments having sanitary connecting webs extending over the tops of said side members, and means driven by the swinging of the seat for actuating said rollers to renew the webs on the tops of said side members. 85
- 10 8. A toilet seat comprising a hinged seat having hollow side members each divided by internal vertical walls into separate supply and winding roll compartments, and detachable bottom sections for said side members carried by said walls. 90
- 15 9. The combination of a forwardly facing U-shaped toilet seat having chambered rear and side members, a supporting yoke member of U-shape having inwardly extending alined journals disposed in bearing openings provided therefor in the sides of said rear member, segmental gear racks secured to the inner ends of said journals within said rear member, gear wheels pivoted within said rear member having a plurality of 100 beveled gears certain ones of which mesh with said gear racks, studs carried by said gear wheels, sleeves rotatable on said studs, a tension spring connecting said studs whereby the gear wheels are urged to rotate about said journals, bevel 105 pinion gears meshing with the other bevel gears of said gear wheels, rotatably mounted pinions supporting said bevel pinion gears, rectangular clutch members connected to said pinions having spring recesses and grooves on opposite faces 110 thereof, drums encircling said clutch members, detents having tongues disposed in said grooves and spring recesses alined with said clutch member recess, compression springs disposed in said recesses and urging said detents into engagement with said drums, whereby the drums are positively driven by said pinions when said seat is raised and the pinions rotate free of the drum when said seat is lowered, sleeves fixed to said side members embracing said drum and extending forwardly therefrom, clutch members connected to said drum within said sleeves having spring recesses and grooves on opposite sides 115
- 20 10. In a device of the class described the combination which a chambered toilet seat, of supply and take-up rolls disposed therein and means for driving said take-up rolls including renewable spools, cup-shaped coupling members disposed within the ends of said spools having polygonal openings and polygonal journals register- 120 ing with said openings for turning said rolls. 125
- 25 11. In a toilet seat, the combination with a yoke having inwardly extending alined journals secured thereto, of a toilet seat having bearing openings housing said journals, racks connected to said journals, gear wheels carried by said seat meshing with said racks, and sanitary roll means connected to said gear wheels, whereby, upon the turning of said seat on said journals, said racks rotate said gears which actuate said sanitary roll 130 means. 135
- 30 12. The combination of a toilet seat having chambered rear and side members, a supporting yoke member having inwardly extending alined journals disposed in bearing openings provided therefor in the end walls of said rear member, segmental racks connected to the inner ends of said journals, gear wheels journaled to said seat and meshing with said racks, spring means connected to said gear wheels, and sanitary rolls 140 connected to said gear wheels. 145

ARCHIBALD I. MCCOLL.
